UNITED STATES PATENT OFFICE.

FRANK E. KELLY, OF MINNEAPOLIS, MINNESOTA, ASSIGNOR OF ONE-HALF TO FREDERICK KEEES, OF MINNEAPOLIS, MINNESOTA.

SMOKE-CONSUMING FURNACE.

No. 871,090.

Specification of Letters Patent.

Patented Nov. 12, 1907.

Application filed October 4, 1906. Serial No. 337,403.

To all whom it may concern:

Be it known that I, FRANK E. KELLY, of Minneapolis, Hennepin county, Minnesota, have invented certain new and useful Improvements in Smoke-Consuming Furnaces, of which the following is a specification.

My invention relates to furnaces and the object of the invention is to prevent the formation of clinkers on the grate and provide for a more complete combustion of the fuel.

10 I am aware that it is old to introduce streams of water into the furnaces beneath the grate bars either with or without the agency of an air blast, and I therefore do not in this application make claim broadly to such construction.

15 My invention consists generally in the manner of mixing the liquid with an air blast and the delivery of the moisture laden air to the grate.

20 In the accompanying drawings, forming part of this specification, Figure 1 is a sectional view of the fire box of a furnace or boiler showing the manner of delivering the moisture laden air beneath the grate. Fig. 2 is a transverse sectional view of the same substantially on a line $x-x$ of Fig. 1. Fig. 3 is a detail sectional view illustrating the manner of delivering the 25 liquid to the blast fan.

In the drawings, 2 represents a boiler, 3 the front of the furnace, 4 the fire box with the grate 5 mounted therein, 6 the bridge and 7 the ash pit.

8 represents horizontal cast iron plenum boxes arranged in the side walls of the ash pit on each side thereof below the level of the grate and substantially opposite one another and flush with the side walls of the fire box as indicated in Fig. 2. These boxes 8 each have a series of holes 9 communicating with the space 35 beneath the grate bars. These boxes, as shown, are set into the masonry and are flush substantially with the vertical side walls of the fire box, so that they do not obstruct in any way the space beneath the grate, and the holes in the boxes are protected to prevent 40 ashes from falling therein.

45 10 represents pipes extending downwardly from the boxes 8 and communicating with a pipe 11 that extends to a fan casing 12 having a blast fan 13 driven from a belt 14. The fan casing 12 has the usual side opening 15 and opposite and contiguous to said opening is a deflector 16 semi-circular in form, mounted on a water supply pipe 17. A plate 18 oppositely curved from the deflector 16 is mounted on arms 19 directly in front of the discharge end of the pipe 17 which is inserted 50 through the middle portion of the deflector 16. A stream of water projected against the plate 18 will be deflected thereby upon the deflector 16 and from thence directed into the interior of the fan casing through the opening 15. The water as it enters the

casing will be in the form of a spray or thin sheet and 55 upon being struck by the rapidly revolving fan will be atomized and mingled with the air which laden with the vapor will be driven through the pipes 10 into the boxes 8 and from thence into the space beneath the grate where it will be evenly distributed and rising 60 through the grate bars will mingle with the burning fuel and air materially in producing more perfect combustion and preventing the formation of clinkers.

65 I have found that water introduced directly into the fan casing will be more thoroughly atomized and the air will be more completely and uniformly charged and will be delivered to the grate in better condition for promoting combustion than where the fan is located in one place and the water introduced at another as has been customary in devices of this kind heretofore 70 used. I have found that the action of the fan will so thoroughly separate the particles of water and mix them with the air current that upon its entry into the fire box it will contain the proper proportion of moisture to produce the best results with the burning fuel. 75 The speed of the fan can be regulated as desired and the volume of water delivered thereto will also be governed by the character of the fuel employed and the percentage of moisture in the air required to prevent formation of clinkers and produce as nearly as 80 possible perfect combustion.

I claim as my invention:

1. The combination, with a furnace grate and its fire box, of plenum boxes arranged in the side walls of said fire box on each side of the grate and below the level of 85 the same and extending from end to end of said fire box, said plenum boxes having a series of perforations in their side walls opening into said fire box, a pipe extending under said fire box and having branch pipes extending laterally to the sides of the fire box and upwardly into the middle portion of said plenum boxes, a blast fan connected with said first named pipe, and means for delivering water into the path of said fan, whereby it will be atomized and the moisture laden currents of air discharged through the 90 perforations in said plenum boxes into said fire box, substantially as described.

2. The combination, with a furnace and its grate, of a blast fan having a discharge opening leading into the fire box, a curved deflector arranged opposite and near the intake opening of said fan, a water supply pipe extending through said deflector and a second oppositely curved deflector arranged in front of said water pipe and against which second deflector the water is discharged and directed therefrom against the curved wall of said first named deflector and from thence delivered in a thin sheet into the 105 path of said fan.

In witness whereof, I have hereunto set my hand this 29th day of September 1906.

FRANK E. KELLY.
